UNITED STATES PATENT OFFICE.

JOHN L. GILL, JR., OF PHILADELPHIA, PENNSYLVANIA.

STEAM-BOILER.

SPECIFICATION forming part of Letters Patent No. 335,750, dated February 9, 1886.

Application filed October 26, 1885. Serial No. 180,897. (No model.)

To all whom it may concern:

Be it known that I, JOHN L. GILL, Jr., of the city and county of Philadelphia, in the State of Pennsylvania, have invented certain new and useful Improvements Relating to Steam-Boilers, of which improvements the following is a specification.

My invention relates, generally, to that class of safety steam-boilers known as "sectional boilers" or "water-tube boilers," in which water from which the steam is generated is contained in a series of tubes or pipes connected at their respective ends by means of chambers and designated as "headers" or "boxes." The water circulating through these tubes and boxes is subjected to the action of heat from a fire located upon a grate beneath, or from the hot gases arising from the products of combustion within the furnace, and the water and steam generated therein are conducted to the steam-drum situated at any suitable distance above the pipes or tubes through pipes leading directly thereto, and as will be fully explained.

My invention consists in making the front and back water-legs of a sectional or water-tube boiler of a series of headers, into which may be secured any suitable number of tubes, preferably arranged at or nearly equal distances apart, in contradistinction to being arranged in vertical rows one above another—that is to say, the tubes are arranged, preferably, one tube above a pair of tubes, or a pair of tubes above a single tube in any desired number of courses, and the sides of the headers made to take a zigzag course in a vertical direction, either in curvilinear or broken straight lines, thereby securing the greatest strength attainable, and so constructed that when a number of headers are placed side by side they will interlock with each other and preserve the general arrangement of the tubes, as above mentioned, at nearly equal distances apart. These headers may be made of a single box, or they may be made up of two or more boxes placed one above the other and connected with one another by means of short nipples.

My invention further consists in casting within each header a suitable number of bridges for the purpose of tying the sides together for holding the bolts by which the covers are se-

cured to the boxes, and in case it should be desirable to use more than one cover on a box one or more of the bridges may be used to form a support for making a steam-tight joint thereupon at the line where the covers meet, and as will be hereinafter more particularly explained.

My invention further consists in connecting the headers directly with the steam and water drum by means of straight or curved tubes without the intervention of saddle-boxes riveted to said steam-drum.

In the accompanying drawings, illustrating my invention, Figure 1 is a side elevation of a sectional boiler occupying a position ready for use with my improved headers secured thereto. Fig. 2 is a sectional elevation showing front and rear views, respectively, of a steam-boiler with my improved headers attached to a series of water-tubes therein and showing the curved pipes leading directly to the steam-drum. Fig. 3 is an outline view showing a front or back water-leg composed of a number of headers of my improved construction, and also showing partly in section the pipes leading to the steam-drum. Fig. 4 is a sectional view in detail of a number of my improved boxes with their respective openings for removing ashes and other foreign matters accumulating upon the outer surfaces of the water-tubes. Fig. 5 is a transverse section of a header, taken on the line xx of Fig. 4, showing a box constructed with the bridge cast therewith, and with a recess in the bridge for the head of the bolt holding the outside cap by means of a nut; and Fig. 6 is a transverse section of a header, also taken on the line xx of Fig. 4, showing the bridge cast therewith, and with means for securing the bolt by which the cap is held to said header.

Similar letters of reference indicate corresponding parts in all the figures.

Referring to the annexed drawings, A represents an ordinary steam and water drum located at any suitable distance above the series of water-tubes B within the furnace-wall C. The water-tubes B are shown in Fig. 1 in a slightly inclined horizontal position, and are subjected to the action of heat arising either from a fire upon a grate, c, beneath or

from the hot gases arising from the products of combustion within the furnace. These water-tubes B may be arranged in any suitable manner, as is well understood, and through them 5 circulate continuously the water and the steam generated therefrom into the respective end chambers or headers, D, thence through the curved or straight pipes E directly to the steam and water drum A, wherein the steam 10 is separated from the water, and the latter circulates downward through the curved or straight pipes into the back water-leg, and thence again through the tubes B, while de- 15 positing any sediment or other foreign matter accumulating in the water-leg into the mud-drum F, of any suitable construction, and located beneath. The pipe E, preferably made of wrought-iron, leading from each header or box, D, is rigidly secured thereto by being ex- 20 panded therein, and in a similar manner it is secured to the steam-drum A; but when the thickness of metal will not warrant the expanding of the tube in the drum a re-enforce plate may be used and placed either upon the in- 25 side or outside thereof. By making these pipes of metal of an elastic nature I am enabled to make due provision for any possible unequal amount of expansion or contraction without bringing any dangerous strain upon their 30 joints.

The front or back water-leg of the boiler may be made of any number of vertical headers, or of such a number as will produce a 35 boiler of the capacity required; and when an odd number of headers is used—for example, one, three, or five—the tube or pipe E, connecting the central header with the steam and water drum A, will be straight in form, while all the other tubes leading directly to the 40 steam-drum will consist of curved pipes. Each header may be constructed in one box, as D in Fig. 3, or it may be made up of a number of boxes, placed one above the other—that is to say, two or more boxes similar to L 45 may be used, one above the other, and nipped together; or two or more boxes like P may be nipped together, one above the other; or combinations may be arranged of L and M; L, M, and L; M, L, and N; M, N, and M, or 50 M, N, M, N, and O, and it will be readily understood that many other combinations may be arranged, according as it may be desired to increase the number of horizontal rows of tubes.

55 As the zigzag boxes illustrated in Fig. 3, having contours consisting of broken straight lines, are susceptible of similar arrangement and use as those having curvilinear contours, a further specific description of them is deemed 60 unnecessary.

Each box of the header must have at least one bridge, H, for the purpose of strengthening the box and for holding the bolt by which the cover is secured to the same. Boxes with 65 two tubes, as O, and boxes with three tubes, as P, require but one bridge. Boxes with four tubes, as N, boxes with five tubes, as M,

and boxes with six tubes, as L, require two bridges. If it is desired to use two covers on a box similar to L, provided with six tubes, 70 a third bridge, H', may be cast within the box for the purpose of forming a support for making a steam-tight joint on it at the meeting line y y.

The bridge H, as shown in Fig. 5, has a 75 hole, h², made in it through which the bolt R is inserted from the inside of the box, and a recess, h', is cast on the under side of the bridge to receive the head of the bolt and to prevent it from turning.

The bridge H, as shown in Fig. 6, has a hole, h², made in it and tapped to receive the tap-bolt S, or a stud-bolt with a thread on each end may be screwed into the tapped hole, and the cover held in its place with a nut, J, as 85 shown in Fig. 5.

The cover I should be made large enough to fully cover the openings and walls f and f' of the box, and so constructed as to conform to the contour of its sides. It is preferably 90 made convex in form, as shown in Figs. 5 and 6, in order to enhance its strength and to resist the steam-pressure from the inside of the chamber or box. The cover is fitted to the box and secured in its place by bolts R 95 and S, and the joint between the box and cover made steam-tight by any of the well-known means for such purposes—for example, a gasket of any suitable material may be used, or the box and cover may be planed and a 100 scraped joint made thereto.

In order to provide for the easy removal of dust, fine ashes, or other foreign matters liable to accumulate upon the upper surfaces of the water-tubes, I arrange a series of semicircular 105 recesses, j, formed by giving the proper contour to the sides of the headers, so that when they are placed side by side or adjacent to one another, two of these recesses will form an opening through which the nozzle of a pipe 110 may be conveniently inserted and a jet of steam or air be effectually used for cleansing the outside of the water-tubes, thereby preserving their full conducting-power of heat. I also utilize the spaces k and k', as shown in Fig. 4 of the 115 drawings, upon the adjacent sides of each pair of headers or boxes at the top and bottom thereof, respectively, for a similar purpose, which will be readily understood. If so desired, the boxes may be constructed without these 120 openings, and due provision made for the cleaning of the pipes or tubes by means of openings left in the side walls of the furnace for this very specific purpose.

Having thus described the nature and objects of my invention, what I claim as new, and desire to secure by Letters Patent, is—

1. As an improvement in steam-boilers, the end chamber, as described, having a series of openings therein for the reception of a corresponding number of water-tubes, and provided with one or more bridges, for the purposes set forth.

2. As an improvement in steam-boilers, the

header, as described, provided with bridges, which allow of a free circulation thereunder and strengthen said header, and when two or more covers are required on a box one or more 5 of the bridges form supports for making a steam-tight joint thereon.

3. As an improvement in steam-boilers, a curved pipe for connecting a header or box directly with the cylindrical surface of a longitudinal steam-drum, substantially as and for 10 the purposes described.

4. The combination, in a water-tube boiler, of the tubes B, header or box D, having openings at the top and bottom thereof for the reception of nipples, of the bridges H, with openings h^2 , and recesses h' , for holding the bolts R, 15 substantially as and for the purposes set forth.

5. The combination, in a sectional steam-boiler, of the tubes B, header or box D, of the bridges H, openings h^2 , of the cap I, and tap or 20 stud bolts S, substantially as and for the purposes set forth.

6. The combination, in a sectional boiler, of the header provided with one or more bridges, the curved pipe leading directly from each 25 header of a series to the longitudinal steam-drum, and a central straight pipe leading directly to said drum, when one, three, or five headers are used, substantially as described.
